UNITED STATES PATENT OFFICE.

ALEXANDER K. RARIG, OF OAKLAND, CALIFORNIA.

DRAINING AND SIRUING MACHINE.

Application filed August 30, 1922. Serial No. 585,326.

To all whom it may concern:

Be it known that I, ALEXANDER K. RARIG, a citizen of the United States, residing at Oakland, in the county of Alameda and State of California, have invented new and useful Improvements in Draining and Siruping Machines, of which the following is a specification.

This invention relates to a machine for use in the canning of fruits and like syrped commodities, and particularly to a machine for draining from the packed cans any surplus water entered therein with the fruit or other commodity, and for supplying a proper amount of syrup to each can preparatory to the final operation of closing or sealing the same.

One object of the invention is to provide a combined draining and siruping machine which is simple of construction, reliable and efficient in operation, and adapted to simultaneously drain and syrup a plurality of cans at a time.

Another object of the invention is to provide an automatic machine of the character described which will have a very large output at a very slow rate of speed of the working parts, with a consequent minimum amount of wear and tear thereon and the securing of greater general efficiency and durability.

A still further object of the invention is to provide a machine whereby cans in series or groups, of any suitable number to a series or group, may first be simultaneously drained and then simultaneously syrped in a rapid and continuous operation, and whereby while one group or series of cans are being drained a preceding group or series will be syrped.

A still further object of the invention is to provide siruping means embodying valves of simple construction which are adapted, without change of size, shape or form, for siruping cans of two or more different sizes, which are adjustable to regulate the amount of syrup to be supplied to the cans according to the size thereof or varying amount of syrup to be supplied to cans of any given size, and which are readily and conveniently removable for cleansing and repairs.

A still further object of the invention is to provide a machine of the character described having operating means of simple construction, which is adjustable to regulate the feed of the cans to the siruping

valves according to the size of the cans to be filled, whereby the cans will be properly centered with relation to the valves.

A still further object of the invention is to provide a machine whereby the cans may be rapidly syrped without the waste of syrup ordinarily occurring through the slopping or spilling of the syrup from the cans.

With these and other objects in view, the invention consists of the features of construction, combination and arrangement of parts, hereinafter fully described and claimed, reference being had to the accompanying drawings, in which:—

Figure 1 is a top plan view, partly in section, of a can draining and siruping machine constructed in accordance with my invention.

Figure 2 is a view in side elevation of the same.

Figure 3 is a vertical transverse section on line 3—3 of Figure 2.

Figure 4 is a vertical transverse section on line 4—4 of Figure 2.

Figure 5 is a view of the cam for raising and lowering the can supporting bed or platform of the siruping device.

Figure 6 is a central horizontal section through the cage of the drain device.

Figure 7 is a vertical section through one of the siruping valves, showing a can in position to be elevated, the valve appearing in closed position.

Figure 8 is a bottom plan view of the valve and its clamps.

Figure 9 is a sectional elevation of the valve and a can in filling position and with the valve open for the filling action.

Figure 10 is a view of the train of mated gears in one of their working positions.

In the practical embodiment of my invention, as herein disclosed, I provide a supporting frame 1 of suitable construction having at one end a feed track or platform 2 and at its other end a delivery track or platform 3. These tracks are suitably constructed for the support and guidance of the cans 4 under treatment, and said tracks are also suitably constructed for the passage therethrough of can engaging fingers 5 upon an endless feed belt or chain 6, whereby the cans are successively engaged by the fingers and moved forwardly to drainage, siruping and discharge or delivery positions. The track 2 may be suitably arranged to permit

the cans to be automatically or manually conveyed theretc from the point where the cans are filled to the desired degree with the fruit from the cooking apparatus or vessels. In practice, more or less surplus water is dipped with the fruit into the cans 4 as they are filled, and one object of my invention is to provide automatic means for draining off this surplus water preparatory to the next stage of treatment, that of supplying the cans with a proper amount of syrup before they are closed or sealed.

The cans placed upon the track 2 are successively engaged and fed forward by a certain number of fingers 5 until a series or group of the desired number of cans is in position to be moved forward into a receiving compartment of a drain cage of a drain device by another or succeeding finger 5 of the chain 6. The drain device referred to comprises a rotary cage 7 centrally mounted upon a longitudinal shaft 8 and having a pair of opposed can receiving compartments 9-9^a communicating respectively through apertured partitions 10 with associated intermediate drain compartments 11, said compartments 11 being separated by a diagonally disposed partition 12 forming a deflector for guiding the drained water toward drain outlets 13.

The cage 7 is movable through a half revolution, i. e., through an arc of 180°, on each can receiving and drainage operation thereof, so as to alternately and simultaneously dispose one of the compartments 9 or 9^a in inverted or drainage position, the group or series of cans being first received from the track 2 into the lower compartment, for example, the compartment 9, after which the cage is rotated to reverse the position of said compartments and thereby invert the cans contained in the elevated compartment 9 for the drainage of the surplus water therefrom, the discharge of the solid contents of the cans being prevented by the apertured partition 10 on which the cans rest during this operation. The compartments 9-9^a are open at each end and thus form passages extending continuously through the drainer 7 from end to end thereof for the successive and intermittent entrance of the cans thereto from track 2 and subsequent transfer of the drained cans from the lower compartment to the siruping device hereinafter described. Slots 14 are provided in the outer walls of the chambers 9-9^a for the passage of the fingers 5 of the conveyor 6 into the lower compartment 9 or 9^a from track 2 or the feed of the cans from said compartment to the siruping device during the feed of the group or series of cans thereto. The drain outlets 13 are arranged in reverse order in the sides of the compartments 11, so as to be disposed at the bottom of the compartment 11 communicating with the elevated

can receiving compartment, the drained water discharging through the working outlet 13 into a collecting trough 15 or the like from which the water may be conducted to any point of discharge. Each time the cage 7 is turned to bring one receiving compartment into receiving position and the other receiving compartment into draining position, said cage remains at rest for a definite or sufficient period to permit the lower receiving compartment to be filled with cans from the track 2, and the previously drained cans contained therein to be discharged therefrom to the siruping device, while the cans in the upper receiving compartment 80 are being drained or relieved of the water. Transverse slots 16, formed in the outer walls of the cage compartments 9-9^a, are provided to align with the fingers 5 which lie between cans of the series disposed in the lower receiving compartment, so as to permit the cage 7 to be turned at proper times without interference from said fingers.

The drained cans are shifted from the drainer to a siruping device including a vertically movable track or platform 17 arranged beneath a syrup tank or receptacle 18, said track or platform being normally disposed between and in horizontal alignment with the bottom wall of the lower compartment of the drainer 7 and the track or platform 3. The group or series of drained cans to be syruped are, at the proper time, shifted by the fingers 5 of the conveyor 6 from the drainer 7 onto the platform 17 beneath syrup discharge nozzles 19. Each of these nozzles 19 comprises a body or casing 20 having a dome-shaped head 21 extending into the tank 18 through an opening 22 in the bottom wall of said tank, said head being provided with ports 23 for the discharge of the syrup from the tank into the body or casing 20. Telescopically fitted over the body or casing, so as to move longitudinally thereof, is a sliding valve sleeve member 24 having at its lower end an annular head 25 forming an outflow passage provided with a conical or beveled valve seat 26. The lower face of this head is formed with an annular groove receiving a gasket 27, of rubber or other suitable elastic sealing material, adapted to bear against the rim edge of the underlying can, to seal the can against the escape of the syrup while the can is being filled therewith. The head 21 is provided with a threaded opening 28 to receive the threaded end 29 of a valve stem 30 carrying an air vent 30' and carrying at its lower end a valve disk or head 31 for cooperation with the valve seat surface 26. Adjustably and detachably secured to the sleeve 24 is a gland or stuffing-box 32 containing a suitable packing to prevent leakage of the syrup between the sleeve and body 20, and enclosing the valve members between the head 25 and a 130

flange or head 33 on the body or sleeve 20 is a coiled spring 34 operating to hold the valve member 24 normally depressed with its seat 27 engaging the valve surface 31 of the valve member 30, thus normally closing the nozzle against the discharge of syrup therethrough. The spring 34, however, allows the valve member 24 to yield or move upwardly under pressure of an elevated can bearing against the head 25, to raise the seat 26 to a greater or less extent above the valve surface 31, thereby providing a passage of greater or less area for the flow of the syrup from the tank to the can as desired or required in the siruping operation. The valve member 30 is provided with an angular upper end 35 for the engagement therewith of a wrench or other suitable tool, whereby said valve member may be adjusted upwardly or downwardly to regulate the height or elevation of its surface 31, and a nut 36, engaging the threaded surface 29, is provided for holding the valve member 30 against displacement in adjusted position. By adjustment of the valve member 30 the degree of opening movement of the surface of the valve member 24 may be regulated with respect to the surface 31 of valve member 30, and the level of the gasket 27 accordingly regulated, so as to adapt the valve to be opened to a greater or less extent on a predetermined upward movement of the underlying can 4. By this means the valves may be adjusted, as occasion may require, to supply a larger or smaller amount of syrup to the cans according to the sizes of the cans or amount of syrup to be filled therein. Clamping members 37, pivotally mounted upon the bottom of the syrup receptacle 18, are provided to engage under the flange 33, for detachably holding the nozzle in working position. It will be observed that the stem 30 holds the elements of the nozzle assembled and also permits of their ready and convenient disassembling for cleaning and repairs, and that by reason of this fact, and the detachable connection between the nozzles and tank afforded by the clamps 37, the nozzles may be easily removed at the end of a day's work for cleaning, to keep them in thoroughly sanitary condition, and as easily and conveniently replaced for use. The cans fed to the parts of the apparatus, as above described, are spaced equidistantly at all times by the fingers 5, and hence the cans moved from the platform 17 will be brought into grouped alignment with the sealing heads 25 of the nozzles. The platform 17 is, of course, provided with a guide slot for passage of the fingers 5 similar to the guide slots in the track 2 and outer walls of the compartments 9 and 9^a.

The mechanism for operating the working parts of the apparatus comprises a main drive shaft 38 journaled transversely of the

frame beneath the platform 17, said shaft having at one end a belt-pulley 39 or the like for receiving driving energy from any suitable source of power. This shaft 38 is continuously driven and at its opposite end carries a mutilated drive gear 40 provided with a toothed surface 41 and an untoothed or blank surface 42, the surface 41 extending around the periphery of the gear to an extent somewhat less than one-half the diameter thereof. The shaft 38 also carries suitable cam mechanism for periodically or intermittently raising and lowering the track or table 17 at properly timed intervals. This cam mechanism is shown, in the present instance, as comprising a cam wheel or disk 43 formed with a cam groove 44 having the opposed low and high groove portions 45 and 46 concentric with and at different distances from its axis, portion 45 extending on an arc somewhat greater than portion 46 on an arc somewhat less than a half circle, said portions 45 and 46 being connected by the offset or eccentric groove portions 47 and 48. Depending from the track or platform 17 is a bracket 49 carrying a roller or other engaging member 50 which fits and travels in the groove 44, whereby in the rotation of the cam the track 17 will be periodically raised and lowered.

Arranged at one side of the driven gear 40 is a mutilated gear 51 mounted on a transverse shaft 52, said gear 51 being provided with two opposed gear segments or toothed surfaces 53 and 54 and intermediate blank or untoothed surfaces 55 and 56. The gear 51 is provided for periodically transmitting motion from the drive gear 41 to the endless feed belt 6, which belt 6 comprises a sprocket chain movable around sprocket wheels 57 and 58, the sprocket wheel 57 being mounted upon the shaft 52 and the sprocket wheel 58 upon a shaft 59. The wheel 58 is fixed to the shaft 59, which is adjustably mounted on the frame 1 for the purpose of taking up any slack in the belt when occasion requires, but the sprocket wheel 57 is loose on the shaft 52 and is adapted to be adjustably secured thereto so that, whenever desired, the can feed motion of the belt 6 may be varied. To this end the shaft 52 has affixed thereto a bracket arm 60 apertured for the passage of a coupling or locking pin 61 adapted to engage any one of a plurality of openings 61' in the sprocket wheel 57, whereby the feed conveyor 6 may be varied or regulated in its feed motion, as occasion may require in the feed of cans of different sizes or diameters, to properly space such cans so that they will be properly centered beneath the nozzles of the siruping device.

At the side of the drive gear 40 opposite the gear 51 is another mutilated gear 62, said gear 62 being mounted on a transverse trans-

mitting shaft 63 and having opposed gear segments or toothed surfaces 64 and 65 and intervening blank or untoothed surfaces 66 and 67. This gear 62 is driven by the gear 40 for imparting two half revolutions or one complete revolution to the drainer 7 on each complete revolution of said gears. Motion is transmitted from the gear 62, when actuated by the gear 40, to the drainer through the transverse transmitting shaft 63 and mitre gears 69 and 70 to a shaft 71 carrying a sprocket wheel 72 connected by a sprocket chain 73 with a sprocket wheel 74 on the shaft 8 on which the drainer 7 is mounted.

15. The operation of the above described machine embodying my invention is as follows:

The cans 4 filled with the fruit or other commodity at the filling point are placed on the track 2 and engaged and fed forward by the conveyor fingers 5, during a movement of the conveyor 6, which, through its intermittent action, is properly timed to feed a determined number of cans in spaced relation on the track 2 and in position to be shifted into the lower compartment of the drainer 7. In the example shown, the machine is constructed for operation upon three cans at a time, a group or series of three cans thus being moved into position on the track 2 ready to be fed up by the fingers 5 of the conveyor 6 on each intermittent working motion of the latter. Figure 2 shows a working arrangement in which three cans which are about to be drained are in position within the lower compartment 9 of the drainer 7 ready to be shifted to draining position, three cans in the top compartment 9^a of the drainer which have been in process of being drained and are ready to be swung downward for subsequent transfer to the siruping device, three cans upon the platform 17 in position to be elevated and siruped preparatory to being shifted from the platform 17 onto the delivery track 3, and three cans upon the track 2 which have been brought into position by a previous working motion of the conveyor 6 in readiness to be delivered to the compartment 9^a of the drainer 7 when said drainer is reversed. Figures 5 and 10 show respectively the positions of the cam mechanism and the parts of the intermittent actuating gearing as they appear under such working conditions above-described. It will be observed by reference to Figure 5 that the cam roller 50 is at point 48, and consequently the platform 17 is in lowered position but about to be quickly raised by portion 46 of the cam groove, and it will be observed by reference to Figure 10 that the toothed surface 41 of drive gear 40 has just moved out of engagement with toothed surface 53 of gear 51 and is about to engage the toothed surface 64 of gear 62, while the blank surface 42 of gear 40 is in engagement with the blank surface

55 of gear 51. Hence on the further movement of gear 40 gear 51 will remain idle, while the gear surfaces 41 and 64 intermesh, thus causing the gear 62 to be given substantially a half revolution until its blank surface 67 engages the blank surface 42 of gear 40. As a result, while the feeder 6 remains stationary, the drainer 7 will be rotated to reverse the position of the compartments 9 and 9^a, bringing the cans in compartment 9 to draining position and the cans in compartment 9^a to discharge position, at which time the motion of the drainer will stop. During this period the cam 43 will make a half revolution, during which the roller 50 will be moved from the point 48 around the high groove portion 46 to the other point 47, thereby raising the platform 17, during which operation the cans on said platform will be siruped. As soon as roller 50 passes point 47, however, and enters the lower groove portion 45, platform 17 descends immediately to normal position, in which it remains during the travel of said roller in said groove portion 45, the siruped cans then being in position for transfer to track 3. At the end of the described working movement of gear 62, blank portion 42 of gear 40 moves into engagement with surface 67 and hence gear 62 remains idle, while gear surface 41 of gear 40 engages gear surface 54 of gear 51, thus transmitting a half revolution to said gear 51. During this movement of gear 51, and until its surface 56 comes into contact with surface 42 of gear 40, the feeder 6 is set into action to force the group of siruped cans from the lowered platform 17 onto the delivery track 3, to force a group of drained cans in the lower compartments of the drainer onto the platform 17, and to force the group of cans on the track 2 into said lower compartment of the drainer 7 in readiness to be inverted for drainage operation on the next reversal of said drainer. Gear surface 41 of gear 40 then comes into mesh with gear surface 65 of gear 62, repeating the operation of reversing the drainer to carry the lower undrained group of cans upward for draining and to carry the group of drained cans downward for discharge to the siruper, during which period the cam roller 50 again travels in the groove portion 46 of the cam 43, thus raising and lowering the platform 17 and effecting the siruping of the group of cans supported on said platform. The apparatus is then ready for a repetition of the cycle of operation above described, in which gear surface 41 of gear 40 engages gear surface 53 of gear 51 and operates the feeder 6 to shift the respective groups of cans from the track 2 to the lower compartment of drainer 7, from lower compartment of drainer 7 to platform 17, and from platform 17 to track 3, as will be readily understood, and it will be apparent

that on each revolution of the main drive shaft the feeder will be actuated for feeding up a group of cans to be drained and syruped and shifting the previously drained and syruped cans from the drainer to the syruper and from the latter to the delivery track 3, the drainer will be operated for simultaneously draining and discharging actions on two successive series or groups of cans, and 5 the syruping device will be operated to syrup a group or series of cans and thereafter bring them in position for discharge. In 10 effecting these operations the working motions of the parts may be very slow, but as groups of cans are handled at a 15 time, a large number of cans may be treated within a given time while the motion of the parts is so even and regulated as to ensure positiveness of the positioning 20 of the cans for each action and an absence of excessive wear and tear upon the moving parts, whereby a durable machine will be produced and one which is not liable to easily get out of order or require frequent 25 shutting down in order to make repairs. The vertical up and down motions, at a comparatively slow rate of speed, of the group of cans to be syruped also ensures a smoothness of action which will prevent the 30 syrup from being spilled out or slopped over and wasted, while at the same time the syruping of a plurality of cans on each operation enables a large number to be syruped within a given working time. A machine 35 constructed in accordance with my invention, therefore, will have a desired evenness, smoothness and regularity of motion, and rapid input and output actions, ensuring the drainage and syruping of a maximum number 40 of cans within a minimum period of time, notwithstanding the comparatively slow rate of movement of the working parts. Inasmuch as there are no parts subject to great wear and tear, and liability of break- 45 age, irregularities or other derangements from rapid motion, the machine will operate constantly and with great uniformity for long periods without shut-downs for repairs or to correct derangements or inaccuracies of 50 operation. Furthermore, the simplicity of the construction adapts the working parts to be readily and conveniently cleaned at the end of each day's operation to maintain the machine in a thoroughly sanitary condition. 55

While I have shown a certain construction of means for carrying my invention into practical effect, it is to be understood that such construction of means may be varied 60 considerably, within the scope of the appended claims, without departing from the spirit or sacrificing any of the advantages of the invention. It will also be understood that while, in the example shown, the ma- 65 chine is constructed to operate upon groups

or series of cans, three in number to a group, its construction may be such as to operate upon a larger number of cans to a group if desired. By the adjustable connection between the shaft 52 and the sprocket wheel 57 the motion of the feeder may be varied to set the fingers 5 backward or forward, for feed retarding or accelerating motion, as occasion may require in the operation of the machine on cans of different sizes. In the 70 present instance I have shown two openings 61 for working adjustments for cans of two different sizes, whereby the working positions of the fingers 5 may be varied to regulate their feed motion according to the size 75 of either of the two sizes of cans generally employed for fruit packing which may be under treatment. By this means the cans in their feed motion will be properly spaced with relation to each other and properly 80 centered on the platform 17 beneath the syruping nozzles for proper sealing contact with said nozzles during the syruping action. 85

While I have shown and described a combined draining and syruping machine, for 90 successively draining and syruping the cans, which is desirable in handling cans packed with fruit, it is to be understood that the machine may be used as a syruper alone in the packing of jellies and jams in which 95 prior draining of the cans is not required. This may be accomplished by either removing the drainer 7 from its shaft 8 or by simply removing or throwing out of action one of the mitre gears 69 or 70, in which latter 100 event the drainer 7 may remain in fixed position, its lower chamber 9 or 9^a forming a guide for passage of the cans from platform 2 to platform 17, as will be readily understood. 105

It will be observed that by my construction of syruper the use of valve mechanism for opening and closing the syrup valves is avoided, also the use and requirement of any special means for keeping a valve from 110 opening in the event that no can is presented beneath it for a syruping action. With my construction the valves are operated (opened) by pressure of an elevated can acting thereon and are self-closing when relieved from 115 the can pressure, and in the event that, from any cause, a full number of cans are not presented on the platform 17 only those valves will be opened which are directly actuated by cans present. I thus dispense with the 120 use of complex and troublesome valve mechanism and prevent waste of syrup in a simpler and more reliable and efficient manner.

Having thus fully described my invention, I claim:—

1. In a combined can draining and syruping machine, the combination of a feeder for feeding groups of cans at a time, a syruper for syruping a group of cans, a drainer having a pair of receiving and draining com- 130

partments and adapted to be inverted to alternately dispose said compartments in receiving and draining positions, and means for operating said parts in timed accord to 5 cause the feeder to supply a group of cans to the receiving compartment of the drainer and to force a preceding group of cans therefrom to the syruper, to invert the drainer upon the cessation of motion of the feeder, 10 and to actuate the syruper during the time period of inversion of the drainer.

2. In a combined can draining and siruping machine, the combination of a frame having feed and delivery tracks, a drainer 15 arranged to receive cans from the feed track, said drainer having a pair of opposed compartments and invertible to alternately dispose said compartments in receiving and draining positions, a syruper disposed between the drainer and delivery track, and means for periodically operating the parts to cause the feeder to feed a group of cans along the feed track into the receiving compartment of the drainer, to force a previously drained group of cans from the receiving compartment of the drainer to the syruper and discharge a group of syruped cans from the syruper onto the receiving track, to invert the drainer during periods 25 of cessation of motion of the feeder, and to actuate the syruper while the drainer is being inverted.

3. In a combined can draining and siruping machine, the combination of a drainer having drain compartments open from end to end thereof to form passages for the feed of cans thereinto and therethrough, said drainer being invertible to alternately bring said compartments into can receiving and can draining positions, a syruper including siruping means and a vertically movable can supporting platform, said platform being normally arranged in alinement with the bottom of the compartment of the drainer 45 which is in receiving position, a feeder provided with feed members movable through the compartment of the drainer which is in draining position and along the platform of the syruper, for successively feeding cans 50 to be drained from a source of supply into the drainer and transferring drained cans directly from said drainer onto the platform of the syruper, and means for periodically operating the drainer, syruper platform and 55 feeder in timed accord.

4. In a can draining and siruping machine, the combination of an intermittently operable can feeder, a drainer having compartments to receive cans from the feeder 60 and movable, between intervals of operation of the feeder, to invert the drainer so as to reverse the positions of the respective compartments between receiving and draining positions, and a syruper adapted to receive 65 drained cans from the drainer on the opera-

tion of the feeder and actuated for a siruping action during the time period of inversion of the drainer.

5. In a combined can draining and siruping machine, the combination of an intermittently operable feeder provided with spaced fingers for feeding a group or plurality of cans at a time, a drainer having compartments to receive groups of cans from the feeder and movable, between intervals of motion of the feeder, for alternately bringing the compartments thereof into receiving and draining positions, and a syruper adapted to receive a group of cans from the receiving compartment of the drainer 70 through the movement of said feeder and operative during the time period of such motion of the drainer for supplying syrup to the cans fed thereto.

6. In a can draining and siruping device, the combination of a intermittently operable feeder, a rotary drainer having opposed compartments alternately movable by rotation of said drainer into receiving and draining positions, and a syruper adapted to 80 receive a plurality of drained cans from the drainer upon the movement of the feeder and operative on a cessation of movement of the feeder to supply syrup to said cans.

7. In a combined can draining and siruping machine, the combination of a frame having can inlet and delivery track portions at opposite ends thereof, a rotatable drainer having drain compartments open at each end and adapted on successive half revolutions 100 thereof to alternately bring said compartments into receiving and draining positions and to dispose the compartment which is in receiving position in line with said inlet and delivery track portions, a siruping device arranged between the drainer and delivery track portion and including pressure actuated siruping valves and a vertically movable platform, said platform being normally disposed in alinement with said inlet and delivery track portions, a feeder 105 provided with fingers for engaging and moving cans along the inlet track portion into the receiving compartment of the drainer and shifting cans from the receiving compartment of the drainer onto the platform of the syruper, and from said syruper platform onto the delivery track portion of the frame, and means for operating the drainer, 110 syruper platform and feeder in timed accord.

8. In a combined can draining and siruping machine, the combination of a frame having inlet and delivery track portions, a drainer having compartments and movable to alternately bring said compartments into and out of receiving and draining positions, the compartment thereof which is in receiving position adapted to aline with said inlet and delivery track portions, a syruper includ- 115 120 125 130

ing a vertically movable platform normally alining with said inlet and delivery tracks and discharge nozzles adapted to be opened and closed on up and down movements of 5 cans supported by said movable platform, and means for periodically operating the feeder to supply cans in groups from the inlet track to the receiving compartment of the drainer, to force drained cans from the 10 drainer to the movable platform of the syruper, and to force syruped cans from said movable platform to the delivery track, said means operating the drainer and movable platform between intervals of operation of 15 the feeder.

9. In a combined can draining and siruping machine, the combination of a frame having inlet and delivery tracks, a rotary drainer having compartments adapted in 20 the rotation of the drainer to be alternately moved into lower receiving position alining with the inlet track and an upper draining position in which the cans are inverted therein, a syruper including nozzles having 25 vertically movable valves and a vertically movable can supporting platform adapted when in normal position to aline with the receiving compartment of the drainer and when elevated to open the valves for supplying syrup to the cans resting thereon, and gearing for periodically actuating the feeder and periodically actuating the drainer and syruper platform in timed accord and between intervals of motion of the feeder.

35 10. In a combined can draining and siruping machine, the combination of a drain device having compartments alternately movable into receiving and draining positions, a syruper for receiving drained cans from the compartment of the drainer which has moved from draining into receiving position, a prime operating means, a feeder periodically actuated thereby for feeding cans to be treated into the receiving compartment of the feeder, feeding the previously drained cans from said compartment to the syruper, and feeding the cans previously syruped by the syruper to discharge position, means actuated by the 40 prime operating means for moving the drainer to reverse the compartments thereof between intervals of motion of the feeder, and means operated by the prime mover between intervals of operation of the feeder 45 for actuating the syruper.

11. In a combined can drainer and syruper, the combination of a rotary drainer having compartments adapted to be successively and alternately brought by rotary movements thereof into receiving and draining positions, a syruper including pressure operated siruping valves and a vertically movable can supporting platform, said platform being normally disposed to receive drained 50 cans from a compartment of the drainer

which is in receiving position, a feeder provided with fingers for moving cans from a source of supply into a compartment of the drainer which is in receiving position and shifting cans previously drained from said compartment onto the syruper platform, a main drive shaft, cam mechanism actuated thereby for intermittently raising and lowering the syruper platform, sets of gearing for operating the drainer and feeder, each 70 including a shaft, mutilated gears on said shafts, and a mutilated gear on the drive shaft for periodically engaging and transmitting motion to the first-named mutilated gears.

80 12. In a combined can draining and siruping machine, the combination of a frame having inlet and delivery track portions, a drainer arranged adjacent to the inlet track portion and having compartments alternately movable into and out of alinement therewith for receiving and draining actions, a syruper having a vertically movable platform normally alining with the aforesaid track portions and receiving compartment of the drainer and valve mechanism actuated by movements of said platform for letting on and cutting off the flow of syrup to cans raised and lowered by said platform, means for periodically operating the feeder 85 for simultaneously feeding a group of cans from the inlet track to the receiving compartment of the drainer, a group of cans from said receiving compartment of the drainer to the syruper, and a group of cans 90 from the syruper to the delivery track, and means for actuating the drainer and syruper between intervals of motion of the feeder.

95 13. In a combined can draining and siruping machine, the combination of a drainer having compartments and movable to alternately bring said compartments into receiving and draining positions, a syruper including syrup supplying means and a can supporting platform vertically movable for 100 moving cans supported thereby to open and close the syrup supplying means, a feeder operative when the drainer and syruper are at rest for shifting cans into the drainer and therefrom into the syruper and from 105 the syruper to a discharge point, and means for periodically operating the drainer to reverse the compartments thereof and actuating the syruper between intervals of motion of the feeder.

110 14. In a combined can drainer and syruper, the combination of a frame having inlet and delivery tracks, a rotary drainer arranged adjacent to the inlet track and having opposed compartments movable alternately 115 into receiving and draining positions, a syruper arranged adjacent to the delivery track and having valve controlled syrup supplying means and a movable platform for raising and lowering cans for actuating said 120 125 130

syrup supplying means, the said inlet and delivery tracks, receiving compartment of the drainer and movable platform of the syruper being disposed in alinement when said parts are at rest, a feeder periodically operative for shifting cans from the inlet track to the receiving compartment of the drainer, from said receiving compartment of the drainer to the platform of the syruper 10 and from said platform to the delivery track, a primary driving shaft, a set of gearing actuated thereby for periodically operating the feeder, and a set of gearing operated thereby for periodically rotating the drainer and raising and lowering the syruper platform between intervals of motion of the drainer.

15. In a combined can draining and sirupping device, the combination of a frame having inlet and delivery track portions, a rotary drainer having compartments alternately movable into receiving and draining positions, a syruper having a vertically movable platform for supporting cans and valve mechanism opened and closed by the raising and lowering of the cans under actuation of said platform, a primary drive shaft, a feeder for shifting cans from the inlet track to the receiving compartment of the drainer, 20 from said compartment to the platform of the syruper and from said platform to the delivery track, a mutilated gear on said shaft, gearing for periodically actuating the feeder including a mutilated gear actuated 25 by the mutilated gear on the primary drive shaft, gearing for periodically rotating the drainer including a mutilated gear also operated by the mutilated gear on the primary drive shaft, and cam mechanism operated 30 by the primary drive shaft between intervals of motion of the feeder for raising and lowering the platform.

16. In a combined can draining and sirupping machine, the combination of a drainer having compartments to receive a group of cans to be drained and subsequently discharged, means for shifting said drainer to periodically move its compartments respectively into receiving and draining positions, 45 a syruper for syruping a plurality of drained cans at a time received from a compartment of the drainer, means for periodically operating said syruper, a feeder for shifting a group of cans to be drained into the drainer, discharging drained cans therefrom to the 50 syruper and discharging syruped cans from the syruper, and means for operating the same while the drainer and syruper are at rest.

60. 17. In a machine for siruping cans, a series of vertically movable siruping valves, a can supporting platform movable toward and from said valves, an endless feeder having fingers spaced to engage and feed cans to said platform in properly centered rela-

tion to the valves, and means for driving said feeder including a shaft, a gear loose on said shaft, and connecting means for adjustably connecting said gear with said shaft for adjusting the feeder and the working positions of its fingers. 70

18. In a siruping device, the combination of a plurality of spaced and vertically movable siruping valves, a vertically movable can supporting platform beneath said valves 75 and having a longitudinal slot, an endless feeder provided with spaced fingers for engaging and feeding a plurality of cans equal in number to said valves onto said platform in properly spaced and centered relation to said valves, said fingers being movable through the slot in the platform, and driving means for adjusting said conveyor and the working positions of the fingers thereof. 80

19. In a siruping machine, the combination of a plurality of spaced and vertically movable siruping valves, a longitudinal slotted and vertically movable can supporting platform below said valves, an endless feed device provided with spaced fingers arranged for movement along the slot of the platform and operative to engage and feed cans onto said platform in properly spaced and centered relation to the valves, a drive 90 shaft, cam mechanism actuated by said shaft for directly raising and lowering the platform at timed intervals, a shaft for transmitting motion to the conveyor, a gear loose on said shaft and actuated thereby to drive 95 the conveyor, connecting means between said shaft and gear for regulating the drive action of the conveyor so as to advance or retard the working positions of the conveyor fingers, and mutilated gears on said shafts 100 for the transmission of motion from one to the other.

20. In a siruping machine, the combination of a group of vertically movable syrup supply valves, a vertically movable longitudinally slotted can supplying platform adapted to support a series of cans beneath said valves, means for raising and lowering said platform, an endless conveyor provided with spaced teeth movable along the longitudinal slot in the platform and periodically operated to supply a group of cans to said platform and to discharge the previously syruped cans therefrom, and drive gearing for actuating said conveyor, including a shaft, a gear loose on said shaft, and connecting means between said shaft and said gear for adjustably connecting the same and fixing the gear to the shaft in adjusted position, whereby the working motion of the conveyor may be regulated to adjust the working positions of the conveyor fingers. 110

21. In apparatus of the character described, a drainer mounted to revolve upon a central axis and having drain compa- 115 120 125 130

ments on opposite sides of said axis alternately movable on each half revolution of the drainer into lower receiving and upper draining positions, each compartment having an outer wall to serve as a bottom support on which the closed end of a can may rest when said can is upright and said compartment is in lower receiving position, and also having a perforate inner wall to serve as 10 a drain support for the open top of the can when said can is inverted and said compartment is in upper draining position, both of said walls being fixed to and rotatable with the drainer, and each compartment being 15 open at each end, whereby cans may be entered at one end of the compartment and moved longitudinally through and discharged from the opposite end of the compartment.

22. In apparatus of the character described, a rotatable drainer provided with a can receiving compartment and having a preliminary movement from a certain position in its orbit of movement, in which 25 orbital position of the drainer the can is upright and the compartment in position for its reception or discharge, to a second orbital position in which the can is inverted and drained, and having a final movement 30 for thereafter returning the compartment and the can contained therein to the orbital position first stated, said compartment being open from end to end, whereby cans may be entered into the compartment at one of its 35 ends and discharged from the compartment at its opposite end, in which can entering or discharging action the drainer is in the same orbital position.

23. In apparatus of the character described, a rotary drainer mounted to revolve upon a horizontal supporting axis, and provided with drain compartments on opposite sides of its axis arranged substantially at an angle of 180° to each other, each compartment comprising relatively fixed outer, inner and side walls, the inner walls being perforated for the drainage of water therethrough, and said compartments being open at each end so as to form a substantially 45 straight line passage therethrough, the drainer being provided with means for discharging the water draining through said perforated inner walls and being movable on its axis to alternately and successively 50 shift said compartments from a lower receiving position to an upper draining position, and vice versa.

24. In apparatus of the character described, a rotary drainer mounted to revolve 55 upon a horizontal axis and having drain compartments on opposite sides of its axis, each compartment comprising relatively fixed outer, inner and side walls, said inner wall being perforate, and each compartment 60 being open from end to end for passage of

cans thereinto and on a straight line therethrough, said drainer being movable on such axis to alternately and successively shift said compartments from a lower receiving 70 position to an upper draining position, and vice versa.

25. In apparatus of the character described, a rotary drainer mounted to revolve upon a horizontal axis and having drain compartments on opposite sides of its axis, 75 each compartment comprising relatively fixed outer, inner and side walls and being open from end to end for passage of cans therein and therethrough, said inner wall having perforations therein, and a draining 80 chamber communicating with each drain compartment through the perforations in said inner wall, and provided with a lateral water discharge outlet, said drainer being movable on such axis to alternately and successively 85 shift said compartments from a lower receiving position to an upper draining position, and vice versa.

26. In apparatus of the character described, a rotary drainer mounted to revolve 90 upon a horizontal axis and having drain compartments on opposite sides of its axis, each compartment being open from end to end for passage of cans therein and therethrough, and each of said compartments 95 having an outer can retaining wall and an inner perforate wall, both walls being fixed to and rotatable with the drainer, drain chambers interposed between said compartments and provided with lateral outlets, 100 and a partition separating said drain chambers from each other, said drainer being movable on such axis to alternately and successively shift said compartments from a lower receiving position to an upper draining 105 position, and vice versa.

27. In an apparatus of the character described, a rotary drainer mounted upon a horizontal axis and provided with drain compartments on opposite sides of its axis, 110 each compartment being open from end to end thereof and having a perforate inner wall and a slotted outer wall, both walls being fixed to and rotatable with the body of the drainer, said drainer being rotatable 115 so as to bring said compartments alternately into receiving and draining positions upon successive half revolutions thereof, a can feeder having feed members movable through the slot in the bottom wall of each 120 compartment when in receiving position, and means for periodically operating the drainer and feeder.

28. In apparatus of the character described, the combination with an endless 125 feeder provided with feed fingers, of a rotary drainer having drain compartments arranged respectively on each side of its axis of rotation, each compartment having a perforate inner wall and a slotted outer 130

wall fixed to and movable therewith, and each compartment being open from end to end for passage of cans therethrough, the fingers of the conveyor being movable 5 through the slot in the outer wall of a compartment in receiving position for feeding cans thereinto and discharging cans therefrom, and means for periodically rotating the drainer and imparting feed motion to the feeder.

29. In apparatus of the character described, a rotary drainer mounted to turn on a horizontal axis and provided with draining compartments on opposite sides of 15 said axis, each of said compartments being open from end to end and having an outer wall provided with a longitudinal slot, an inner perforate wall and side walls having spaced pairs of transverse slots, said walls 20 being fixed to and rotatable with the drainer, and said drainer also having drain chambers.

communicating through the perforate inner walls with the compartments and provided with lateral drain outlets, said drainer being adapted on each half revolution thereof to 25 alternately and successively dispose said compartments in receiving and draining positions, and an endless can feed conveyor having fingers movable through the slotted bottom wall of either drain compartment 30 when in receiving position for shifting cans into said compartment through one end thereof or from said compartment through the opposite end thereof, said fingers adapted to register with said transverse slots when 35 the feeder is at rest, and means for periodically and successively turning the drainer to reverse the positions of its compartments and actuating the feeder between intervals 40 of motion of the drainer.

In testimony whereof I affix my signature.

ALEXANDER K. RARIG.
